INVENTOR.
Simon E. Schroeder,

UNITED STATES PATENT OFFICE.

SIMON E. SCHROEDER, OF NEWTON, INDIANA.

WRINGER.

Application filed February 28, 1927. Serial No. 171,491.

My invention relates to clothes wringers and has for one of its objects the provision of means for quickly and easily relieving the pressure between the rolls of the wringer and at the same time disconnecting one of the rolls so that it can be readily separated from the other.

It is a further object of my invention to provide a clothes wringer which may be substantially and rigidly constructed and which, while accomplishing the above results will contain few parts readily manufactured and assembled.

For the purpose of disclosing my invention I have illustrated an embodiment of the same in the accompanying drawings in which—

Fig. 1 is a front or rear elevation, partly in section, of a wringer embodying my invention;

Fig. 2 is a partial end elevation thereof, partly in section, and

Fig. 3 is a detail section showing the locking mechanism between the front roll and the pressure applying means.

In the embodiment of the invention illustrated I provide a frame preferably formed of sheet metal and comprising a bottom channeled member 1 open on its under side and side channeled members 2 open at their tops and having on their inner faces slots 3 to accommodate the shafts of the wringer rolls. Arranged within the channels of the side members 2 are bearing blocks 4 on which are adapted to rest the ends of the shaft 5 of the bottom roller 6. One of the side members 35 has its outer wall slotted as at 7 to accommodate the extending squared end 8 of the shaft 5 which is adapted to receive power applying means for turning the roll.

A flat spring 9 is mounted within the channel of the bottom member 1 and is bowed at its center and adapted to bear through the medium of an adjusting screw 10 on the under face of the top of the bottom member 1. The free ends of the spring are adapted to be connected to vertically extending slidable connector bars 11 mounted within the channels of the side members 2 and between the end walls of the members and the bearing blocks 4.

These connector bars at their lower ends are provided with inturned lips 12 engaging beneath the free ends of the spring, and extending through these lips and the free end of the spring and connected to the top of the bottom member 1 are threaded members 13 having at their lower ends nuts 14 which act

as limit stops for the connector bars 11. The upper ends of the connector bars 11 are conveniently guided in their vertical sliding movement by pins 15 operating in slots 16 in the end walls of the side members 2.

Mounted above the bearing blocks 4 are bearing blocks 17 which are slidable in the channel ways of the channel members 2 and have mounted therein the shaft 18 of the upper roll 19 which roll is adapted to bear upon the lower roll 6 and be held thereagainst under the pressure exerted by the tension of the spring 9. To this end the bearing blocks are adapted to be connected to the upper ends of the connector bars 11 by a releasable connection. Pivottally connected to each of the bearing blocks 17 is a swinging arm 20 mounted on a pivot pin 21 on the outer face of the bearing block 17 and to provide a rigid mounting therefor. The bearing block may be faced with metal as at 22 which facing at its upper end has an inturned flange 23. Each of the arms 20 is provided with an out turned ear 24 adapted, when the arm 20 is swung to place the ear in vertical alignment with the shaft 18, to engage beneath an inturned ear 25 formed on the upper ends of the connector bars 11 and when this engagement is effected, place the spring 9 under tension to effect a pressure between the upper roll 19 and the lower roll 6. The arms 20 are connected together by a top bail or cross bar 26 by which they may be simultaneously operated and which is conveniently located above the wringer roll 19 and in a position to be readily struck by the operator.

The operation of the device is obvious. As long as the ears 24 and 25 are in engagement the upper roll will be connected to the spring 9 by means of the connector bars 11 and the spring 9 placed under tension so that the upper roll 19 will be held in pressure relation with respect to the lower roll. As soon as the bail member 26 is swung on the pivot pins either toward or away from the operator the ears 24 will be disengaged from beneath the cam ears 25 thereby disconnecting the upper roll 19 from the connector bars 11 and likewise from the spring 9, relieving the pressure of the upper roll and permitting, if desired, the entire removal of the upper roll. The lower roll may be readily removed after the upper roll is removed by tilting the same so as to clear that end of the roll opposite the squared portion 8 of the top of the side member 2 and then withdrawing the roll

axially from position. In addition to the slot 7 in the end wall of the side member to accommodate the shaft 5 the connector bar 11 is similarly slotted as at 27. To accommodate 5 the swing of the arms 20 the side faces of the side members 2 are slotted at their upper ends as at 28.

The wringer may be conveniently provided with any form of drain board as 29 10 and with any desired form of flow director 30.

I claim as my invention:

1. In a clothes wringer in combination, a frame, a lower roll mounted therein, an upper roll mounted therein and movable relatively to the lower roll, pivot members connected to the upper roll, pressure applying means mounted in said frame below said lower roll, connector members connected to 20 said pressure applying means and having engaging lugs, and swingable members pivotally mounted on said pivot members and having engaging lugs arranged to engage the lugs on said connector members when the 25 swingable members are swung into vertical alignment with the shafts of the wringer rolls.

2. In a clothes wringer in combination, a frame, a lower roll mounted in said frame, an upper roll mounted in said frame and 30 movable relatively to the lower roll, pivot members connected to the upper roll, a bar spring mounted in said frame beneath said lower roll, connector members connected to 35 the free ends of said spring each having an engaging lug, swingable arms pivotally mounted on said pivot members, and connecting lugs on said arms arranged to be engaged with the lugs on the connector members when

the arms are swung into vertical alignment 40 with the shafts of the rolls.

3. In a clothes wringer, in combination, a frame, a lower roll mounted in said frame, an upper roll removably mounted in said frame and movable relatively to the lower 45 roll, pivot members connected to the upper roll, a spring mounted in said frame beneath the lower roll, connector members connected to the ends of said spring and having engaging lugs and a swingable bail mounted on 50 said pivot members and having engaging lugs arranged to be engaged with the lugs on said connector members when the bail is swung to a position in vertical alignment with the shafts of the rolls. 55

4. In a clothes wringer, a frame including channeled side members, a lower roll having bearing blocks supported in the channel ways of the side members, an upper roll having bearing blocks slidably mounted in the channel ways of the side members, a bar spring mounted in said frame beneath the lower roll, connector bars, slidably mounted in the channel ways of the side members and connected at their lower ends to the ends of 65 the bar spring, engaging lugs on the upper ends of said connector members and swingable arms pivoted on the bearing blocks of the upper roll each having a lug arranged to engage the respective lugs of the connector 70 members when the swingable arms are swung into vertical alignment with the shafts of the rolls. 75

In witness whereof, I SIMON E. SCHROEDER have hereunto set my hand at Newton, Iowa, 75 this 24 day of February, A. D. one thousand nine hundred and twenty seven.

SIMON E. SCHROEDER.
